UNITED STATES PATENT OFFICE

2,498,428

SERVING TABLE ADJUSTABLE AND
PORTABLE

Albert Kruse, Los Angeles, Calif.

Application June 25, 1947, Serial No. 757,032

1 Claim. (Cl. 311—21)

1 This invention relates to improvements in adjustable carriers or stands.

An object of the invention is to provide an improved form of adjustable carrier or stand which will be supported at about waist height in front of a person for supporting suitably shaped dishes to assist an invalid or blind person to more easily and readily feed himself.

Another object of the invention is to provide an improved adjustable carrier table or stand adapted to be supported at approximately waist height in front of a person.

A further object of the invention is to provide an improved adjustable carrier table or stand which will be highly efficient in use, and relatively inexpensive to manufacture and produce.

Other objects will appear as the description proceeds.

In the accompanying drawings which form a part of this application,

Figure 1 is a side elevation of the improved carrier table or stand shown in open position;

Figure 2 is a side elevation of the improved carrier table or stand shown in folded position;

Figure 3 is a rear elevation of the improved carrier table or stand;

Figure 4 is a detail view of one of the turned down supporting ears at the rear end of the carrier table or stand.

Like characters of reference are used throughout the following specification and the accompanying drawings to designate corresponding parts.

In carrying out the invention, there is provided an improved form of adjustable and portable carrier table or stand including a flat supporting table surface generally designated by the reference numeral 1, the same having its opposite ends 2 and 3 bent upwardly a slight distance to prevent dishes (not shown) when placed on the carrier table or stand from sliding or falling off of the same.

An upwardly directed transversely extending guard flange or rail 4 is hinged at 5 to the forward edge of the table surface 1, being of considerably more height than the said end guard flanges or rails 2 and 3.

Centrally disposed securing ears 6 and 7 are formed at the opposite ends of the front guard flange or rail 4 and are of a reduced length, being adapted to cooperate with the oppositely disposed fastening hooks 8 and 9 pivotally supported in the suitable apertures 10 formed through the outer ends of said end guard flanges or rails 2 and 3. When the front guard flange or rail 4 is in

raised position, the hooked outer ends of the hooks 8 and 9 will extend over said ears 6 and 7 to support the said flange or rail 4 in fixed position.

The opposite ends of the table surface 1 are cut inwardly at 11, and the supporting ears 12 are bent downwardly and formed with the aligned central aperture 13 between which and through which the cross pivot rod 14 is adapted to extend. A bearing collar 15 is adapted to be placed about the shaft or rod 14 to extend between said supporting ears 12.

A pair of vertically disposed spaced frame members 16 and 17 are formed with the elongated slots 18, through which the opposite ends 15 of said rods 14 are slidably and adjustably received. A head 19 will be formed on one end of the rod 14, while the opposite end thereof is threaded at 20 to receive and support the wing locking nut 21.

20 A bearing rod 22 extends through the lower ends of the spaced frame members 16 and 17, and supports the U-shaped table bracing link 24. The ends of said links 24 are bent or looped at 25 and 26 to extend about the bearing rod 22, 25 while the base of the link is pivotally supported in the U-shaped bearings 27 and 28 suitably secured to the lower surface of said table 1.

The upper ends of said spaced frame members 16 and 17 are formed with apertures such as 29, 30 which are connected by reduced or narrowed slots such as 31 with the upper ends of the slots 18 in said frame members.

35 The upper end links 33 of the crossed attaching and supporting chains 35 are secured in the apertures 29, while the lower end links 36 of said chains 35 are secured about the opposite ends of the bearing rod 22.

When not in use, the carrier table or stand may be folded as shown in Figure 2 of the drawings. 40 When the carrier table or stand is to be used, the table surface 1 will be extended forwardly of the frame members 16 and 17 and the wing nut 21 tightened. The supporting chains 35 will then be disposed over the supporting object.

45 From the foregoing description, it will be apparent that there has been devised and provided a highly efficient form of adjustable carrier table or stand for invalids and blind persons which will be relatively inexpensive to manufacture and produce.

50 While the preferred embodiment of the instant invention has been illustrated and described, it will be understood that it is not intended to limit the scope of the invention thereto, as many minor changes in detail of construction may be resorted

to without departure from the spirit of the invention.

Having thus described my invention what I claim as new and desire to secure by Letters Patent of the United States is:

An adjustable carrier table comprising a pair of spaced parallel frame members having longitudinally extending slots therein, a transverse shaft slidably retained in the slots, a table member inwardly cut at opposite ends thereof and having downwardly bent apertured ears thereat, said shaft extending through said ears, a second transverse shaft carried at the bottom of said frame members, a U-shaped brace secured at its ends to said second shaft and pivotally attached at its central portion to said table member, upstanding guard flanges at the edges of said table member, a front guard flange hinged to the forward edges of said table member and upwardly above the level of said end guard flanges, locking ears on 20

the opposite ends of said front guard flange, and hooks pivotally attached to said table member and engageable with said locking ears for holding the same in operative position.

ALBERT KRUSE.
